[57] CLAIM

The ornamental design for climbing exerciser, as shown and described.

DESCRIPTION

FIG. 1 is a front perspective view of a climbing exerciser showing our new design;

FIG. 2 is a side elevational view thereof, the side opposite being substantially a mirror image;

FIG. 3 is a front elevational view thereof;

FIG. 4 is a rear elevational view thereof;

FIG. 5 is a top plan view thereof; and,

FIG. 6 is a bottom plan view thereof.

*Fig. 1.**Fig. 2.*

*Fig. 3.**Fig. 4.*

Fig. 5.

Fig. 6.
